CELLULOSE DIGESTER

Fritz Krüger, Mannheim-Waldhof, Germany, assignor to Zellstofffabrik Waldhof, Mannheim-Waldhof, Germany

Application November 5, 1931, Serial No. 573,287,
and in Germany December 30, 1930

2 Claims. (CL. 92—7)

Up to now in cellulose digesters provided with pump operated circulation the portion of the circulating conduit situated within the digester has been constructed in various ways. For example the said conduit has been led up to only the inner surface of the digester wall and covered with a sieve member or it was allowed to open into annular channels which likewise were covered with sieve members. Sometimes the ends 5 of the pipe were also led to the middle of the digester and were provided with fine apertures on the surface of their casing through which the lye was sucked or ejected. Covering with sieves is a bothersome and very expensive arrangement; furthermore it also has the disadvantage that should any disturbances arise the orifices of the tube are difficult to access and that in the course of time leakages readily form at the edges of the sieve plate members. Moreover, the annular channels arranged in the lining 10 of the digester and formed by the bricks of the lining are only slightly resistant and in the case of the unavoidable loosening of the structure of the wall, the said annular channels 15 easily become deteriorated through chemical and mechanical influences. The introduction of the said conduits into the middle of the digester, either as a straight pipe end or as a worm and so forth, has the great disadvantage that the 20 portion of the interior of the digester adjacent to the conduit is rendered difficult to access and any repairs that may be necessary are made very difficult, and in addition when the digester is emptied the portion of the circulating conduit 25 projecting into the interior of the same forms a disadvantageous obstacle.

These disadvantages are avoided by the new device in that the portion of the conduit lying within the digester consists of a circular conduit 30 provided with fine openings which is situated in the proximity of the wall of the digester or is arranged even in the lining of the digester in such a way that only a portion of the cross section of the conduit projects beyond the said 35 lining.

The accompanying drawing shows in cross section a device according to the present invention by way of example.

Figure 1 shows a sectional elevation of the 40 lower part of the digester provided with the device according to the invention, whilst Figure 2 shows on a larger scale a cross section of a portion of the lining of the digester with the circular conduit embedded therein.

55 The portion of the conduit situated within the

interior of the digester, connected by means of the members *a a'* to the exterior pipe, consists of the circular conduit *c* connected with the members *a a'* through the supply pipes *b b'*, the greater part of the cross section of the said 60 circular conduit *c* being embedded in the lining *d d'* of the digester, as is apparent from Figure 2 which is drawn on an enlarged scale. The circular conduit *c* is provided at the free part with fine openings *e e'* through which the lye 65 is sucked or ejected.

The device constructed in the said manner is naturally applicable independently of the construction and arrangement of the other parts of the forced circulation arrangement. For example the pumps producing circulation of the lye may be arranged outside the digester or within the casing thereof, or a special lye heater may be inserted in the circulation conduit, for example, and so forth.

70 75 75

What I claim is:

1. A cellulose digester having fluid conduits for the pump-operated circulation of the digesting lye, the parts of the fluid conduits lying within the digester consisting essentially of an 80 annular pipe of circular cross-section, perforated on one side to provide sieve-like apertures and a short supply pipe therefor arranged close to the wall of the digester whereby fluid will be squirted in divergent jets into the digester.

85

2. A cellulose digester having fluid conduits for the pump-operated circulation of the digesting lye, the parts of the fluid conduits lying within the digester consisting essentially of an annular pipe of circular cross-section, perforated 90 on one side to provide sieve-like apertures and a short supply pipe arranged in the wall of the digester so that only a sieve-like perforated portion of the surface of the conduit projects into the interior of the digester whereby fluid will 95 be squirted in divergent jets from the conduit into the digester.
